TAG HOLDER

Vyto Simkus, Chicago, Ill., assignor to American Flange &
Manufacturing Co., Inc., New York, N.Y.

Filed Mar. 19, 1971, Ser. No. 126,383

Term of patent 14 years

Int. Cl. D8—08

U.S. Cl. D8—243

FIG. 1 is a top plan view of a tag holder embodying my new design; and

FIG. 2 is a fragmentary cross sectional view taken on line 2—2 of FIG. 1.

I claim:

The ornamental design for a tag holder, substantially as shown.
